UNITED STATES PATENT OFFICE

JOHN C. CURTIS, OF CLEVELAND, OHIO, ASSIGNOR TO THE CLEVELAND ROCK DRILL COMPANY, OF CLEVELAND, OHIO, A CORPORATION OF OHIO

SHEATHING DRIVER

Application filed August 28, 1931. Serial No. 559,875.

This invention relates to improvements in sheathing drivers and more specifically to apparatus for use with fluid actuated tools of the percussive type, such for example as rock 5 drills.

In adapting portable tools for driving sheathing, piles or similar material, it is customary to employ an anvil block which is so proportioned as to engage the major area of 10 the end of the sheathing stock. The anvil and adaptor frame therefore are usually borne by the tool and are so constructed as to accommodate its addition to the forward end of the cylinder of the tool, and are likewise so formed as to support a guide member 15 or sheathing saddle adapted for engagement upon the work.

One of the pre-requisites in the design of 20 sheathing saddles of this type is that some provision must be made to accommodate the device to the variable thickness of stock usually encountered. Cheek plates or shims interposed between the side walls of the saddle and the pile have heretofore been commercially employed but it has been found that the 25 selection of the most suitable plate and the adjustment thereof entails considerable labor, particularly when it is found necessary to make such adjustments in field work. Furthermore, the sheathing saddles which have 30 been formed to accommodate cheek plates have been so constructed as to inhibit the structural adaptability of wrought iron or steel bar-stock forgings, and other similar 35 light stock which is capable of sustaining the vibratory strains imposed upon the sheathing saddle.

One of the objects of this invention, therefore, is to construct a sheathing saddle or 40 guide member of light bar stock which is suitable in strength and structurally susceptible of withstanding the vibratory strains and bending forces to which it is subjected.

Another object of this invention is to 45 construct an anvil adaptor frame and sheathing saddle which may be readily adjusted to accommodate different thickness of sheathing stock without the necessity of employing removable cheek plates or spacer blocks.

50 Another object of this invention is to pro-

vide a sheathing guide comprising separable elements which may be adjusted, removed or renewed in part.

Another object of this invention is to construct a sheathing saddle which is relatively 55 light in weight, accessible of adjustability, durable of construction and economic of manufacture.

Other objects more or less ancillary to the foregoing and the manner in which all of the 60 various objects are realized will appear in the following description, which considered in connection with the accompanying drawing, sets forth the preferred embodiment of the 65 invention.

In the drawing,

Fig. 1 is a central vertical section of the 70 anvil block, adaptor frame and sheathing saddle illustrating the preferred embodiment of this invention.

Fig. 2 is a vertical sectional view of the 75 anvil block and its appurtenances taken on a plane, substantially 90° to the illustration of Fig. 1 and indicated by line 2—2 in Fig. 1.

Fig. 3 is a detail elevational view of the 80 sheathing saddle and a fragmentary portion of the anvil block illustrating the contour and the relation of the respective parts of the device.

Figure 4 is an underneath plan view of the 85 sheathing driver.

The device comprises in its general organization an anvil block adaptor frame 10 which is suitably secured upon the forward portion of the cylinder (not shown) by means of side 85 bolts 11. The adaptor frame is bored to receive an anvil block 12 which is provided with a stem 15 adapted to be struck intermittently by the hammer (not shown) of the rock drill. The lower face of the anvil is provided with a plurality of pins or spikes 13 arranged for engagement with the sheathing material or pile 14. The adaptor frame 10 is formed with laterally extended flanges 16 apertured with intersecting bolt holes 17 and 17'. The 95 guide member or sheathing saddle comprises a pair of formed stanchions 18 and 28 respectively which may be supported by the adaptor frame in either the bolt holes 17 or 17'. The selectivity in assembly of the stan- 100

chions within the spaced apertures 17 and 17' facilitates the accommodation of the saddle to the variable thickness of sheathing usually encountered. The stanchion 18 embodies 5 a pair of parallel arms 19 having enlarged portions 20 providing abutments 21 which are drawn against the flanges 16 by nuts 22 upon the threaded ends of the arms 19. The lower looped portion of the stanchion 18 is 10 extended inwardly as at 23, upwardly as at 24 and looped laterally as at 25 to form a foot rest adapted to receive the weight of the operator thereon. The arenated portions 23 and 24 of the looped foot rest assure 15 the rigidity of the foot rest and amplify the cramping action of the loop 23 against the piling when the tool is in use. The stanchion member 28 likewise embodies parallel arms 29 similarly selectively secured within apertures 17 or 17' in the flanges 16. The lower ends of these arms 29 extend inwardly as at 30 and upwardly as at 31 in the plane of the parallel arms 29 and thus form an inverted U-shaped loop 37, the top of which is provided to limit the downward movement of 25 the anvil block 12.

In the application of the device the sheet or pile 14 extends between the stanchions 18 and 28 of the saddle with the anvil block 12 resting upon the end of the pile and with the spikes 13 extending thereon. The weight of the operator is thrown upon the foot rest 25 and as the hammer of the drill strikes the anvil block 12 the sheathing is driven downwardly. The crest of the loop 37 retains the anvil block 12 and is formed to suitably limit its downward movement. When the sheathing to be driven is relatively narrow the stanchion arm may be secured within the 35 bolt holes 17, and as wider sheathing is encountered the saddle may be widened by securing the arms of either or both of the sets of apertures 17'.

Referring to Fig. 4, it will be noted that 45 the anvil frame is substantially rectangular and that the apertures 17 and 17' are disposed adjacent the corners thereof. It will be further noted that the anvil block is formed with tongues 38 which extend between the arms 19 and 29 to prevent rotative 50 movement of the anvil during the operation of the tool.

The employment of bar stock in the construction of the stanchions not only facilitates 55 economic manufacturing practice but provides a structural advantage over baser materials, such as castings, as the use of the rods or bar stock assures a relatively light structure which is capable of resisting the 60 vibratory strains to which it is subjected.

A further advantage of the design resides in forming the anvil saddle of separate stanchions which may be independently adjusted, interchanged or renewed.

65 It will be seen, therefore, that the sheath-

ing saddle herein described is extremely simple in its construction and may be manufactured at a very low cost. It will also be seen that the apparatus is comprised of a pair of separate units which may be independently 70 positioned with respect to each other. The invention is not to be limited to the exact arrangement of parts or structural detail shown in the accompanying drawing, or described in this specification, as various 75 changes in the detail may be resorted to without departing from the spirit of the invention as herein claimed.

What I claim is:

1. In combination, an anvil frame adapted 80 to be secured to a sheathing driver, members of looped rod stock having their ends secured to said frame, said members providing a plurality of elements extending substantially parallel in a direction substantially that of the direction of the reciprocation of the anvil, said members being spaced apart to receive the end of the sheathing, an anvil carried in said frame and provided with lateral portions adapted to engage and be guided by the elements of said members.

2. In combination, an anvil frame adapted 85 to be secured to a sheathing driver, members of looped rod stock having their ends secured to said frame, said members providing a plurality of elements extending substantially parallel in a direction substantially that of the direction of the reciprocation of the anvil, said members being spaced apart to receive the end of the sheathing, an anvil carried in said frame and provided with lateral 90 portions adapted to engage and be guided by the elements of said members, one of said members having a looped portion extending laterally from the said plane and arranged 95 to provide a foot rest for an operator.

3. In combination, an anvil frame adapted 100 to be secured to a sheathing driver, members of looped rod stock having their ends secured to said frame, said members providing a plurality of elements extending substantially parallel in a direction substantially that of the direction of the reciprocation of the anvil, said members being spaced apart to receive the end of the sheathing, an anvil carried in said frame and provided with lateral 105 portions adapted to engage and be guided by the elements of said members, said anvil blocks having a laterally extending portion 110 adapted to engage with and be limited in movement by a looped portion of at least one of said members.

4. In combination, an anvil frame adapted 115 to be mounted upon a sheathing driver, laterally extending ears on said frame, members of looped rod stock having their ends threaded and extending through apertures in said ears, nuts threaded on the ends of said members and uniting the members to the frame, 120 said members having elements extending sub- 125

stantially in a plane parallel to the direction of reciprocation of the anvil, said members being spaced apart to resiliently receive the end of the sheathing.

5. In combination, an anvil frame adapted to be mounted upon a sheathing driver, laterally extending ears on said frame, members of looped rod stock having their ends threaded and extending through apertures in said 10 ears, nuts threaded on the ends of said members and uniting the members to the frame, said members having elements extending substantially in a plane parallel to the direction of reciprocation of the anvil, said members 15 being spaced apart to resiliently receive the end of the sheathing, an anvil reciprocable in said frame and having lateral portions adapted to be engaged with and be guided by said elements.

20. In combination, an anvil frame adapted to be mounted upon a sheathing driver, laterally extending ears on said frame, members of looped rod stock having their ends threaded and extending through apertures in 25 said ears, nuts threaded on the ends of said members and uniting the members to the frame, said members having elements extending substantially in a plane parallel to the direction of reciprocation of the anvil, 30 said members being spaced apart to resiliently receive the end of the sheathing, an anvil reciprocable in said frame and having lateral portions adapted to be engaged with and be guided by said elements, one of said 35 members having a looped portion extending laterally from the said plane and arranged to provide a foot rest for an operator, said anvil block having a laterally extending 40 portion adapted to engage with and be limited in movement by a looped portion of at least one of said members.

7. The combination with a sheathing driver having a reciprocating anvil block for engagement with the sheathing and an apertured anvil frame, of a sheathing guide consisting of a pair of spaced stanchions formed of looped rod stock and having their free ends projected through said apertures and adjustably locked to said frame, the looped 45 portions of the stanchions extending substantially parallel in the direction of reciprocation of the anvil and being adapted to receive the end of sheathing therebetween.

8. The combination with a sheathing driver having a reciprocating anvil block for engagement with the sheathing and an apertured anvil frame, of a sheathing guide consisting of a pair of spaced stanchions formed of loop rod stock and having their free ends 50 projecting through said apertures and adjustably locked to said frame, the looped portions of the stanchions extending substantially parallel in the direction of reciprocation of the anvil and being adapted to resiliently receive the end of the sheathing.

therebetween, one of said loop portions having the extremity thereof projected outwardly at substantially right angles to the plane of the stanchions to provide a foot rest for an operator.

In testimony whereof I hereunto affix my signature this 25 day of August, 1931.

JOHN C. CURTIS.
